UNITED STATES PATENT OFFICE

157,928

BAG OR THE LIKE

Oscar L. Vines, New York, N. Y.

Application June 26, 1948, Serial No. 147,235

Term of patent 14 years

(Cl. D58—2)

To all whom it may concern:

Be it known that I, Oscar L. Vines, a citizen of the United States, residing in New York city, county of New York, and State of New York, have invented a new, original, and ornamental Design for a Bag or the like, of which the following is a specification, reference being had to the accompanying drawing, forming part thereof.

In the drawing:

I claim:

The ornamental design for a bag or the like, as shown,

OSCAR L. VINES.
